UNITED STATES PATENT OFFICE.

HENRY T. BRODEN, OF BROOKLYN, ASSIGNOR TO THE STANDARD CUT GLASS COMPANY, OF NEW YORK, N. Y.

DESIGN FOR A GLASS DISH.

SPECIFICATION forming part of Design No. 24,960, dated December 10, 1895.

Application filed September 21, 1895. Serial No. 563,257. Term of patent 7 years.

To all whom it may concern:

Be it known that I, HENRY T. BRODEN, a citizen of the United States, residing at Brooklyn, in the county of Kings and State of New York, have invented a new and original Design for a Glass Dish, of which the following is a specification, reference being had to the accompanying drawings, forming a part thereof, in which—

- o Figure 1 is a plan view of a vessel embodying the features of the design, and Fig. 2 is a transverse section taken substantially on the line 2 2 of Fig. 1.

The design is applicable to any kind of glass dishes, such as bowls, plates, and jugs.

The said design consists of a series of prisms extending from edge to edge of the vessel, the prisms crossing one another, forming at intervals a prismatic, multiple-pointed star; and between the prismatic stars the aforesaid prisms form a number of polygonal panels.

I claim—

The design for a glass dish herein shown and described.

HENRY T. BRODEN.
